P. G. EKSTROM.
METHOD OF NEUTRALIZING ACID LYES.
APPLICATION FILED FEB. 24, 1912.

METHOD OF NEUTRALIZING ACID LYES.

1,098,561.

Specification of Letters Patent.

Patented June 2, 1914.

Application filed February 24, 1912. Serial No. 679,792.

To all whom it may concern:

Be it known that I, PER GÖSTA EKSTRÖM, a citizen of the Kingdom of Sweden, residing at Harnäs, Sweden, have invented a new and useful Improved Method of Neutralizing Acid Lyes, of which the following is a specification.

It is well known that by boiling cellulose matters for instance, wood, peat, and the like, with acid liquors a liquor can be obtained which after neutralization with suitable basic agents as for instance lime, and oxidation by aerating can be used for the manufacture of alcohol by usual alcoholic fermentation.

This invention relates to an improved method of carrying out the neutralizing and aerating process of such liquors by means of which it is possible to treat in an effective and rapid manner large quantities of liquor.

The invention consists, chiefly in effecting a rapid action of the neutralizing agent in such manner that, after introduction of the liquor to be treated and the neutralizing agent into a reservoir, compressed air is blown from below through the liquor in an upward whirling motion thereby effecting an intimate mixing of the liquor and the neutralizing agent and accelerating the action of the latter. When the neutralizing process is completed the air supply is interrupted whereupon the solid matters in the liquor are left to sink toward the bottom of the reservoir, the clear liquid in the surface layer being continuously drawn off by means of a siphon pipe carried by a float so as to accelerate the separation of the neutralized liquid from the solid matters contained therein.

For the purpose of removing the sediment from the bottom of the reservoir, said sediment consisting partly of neutralizing agent that has not been consumed and partly of unsoluble compounds formed during the neutralizing process, I then introduce into the reservoir from below water under pressure in a whirling motion so as to stir up the sediment in the water which is then together with the said sediment drawn off from the reservoir before the solid matters have again deposited on the bottom.

I will now more fully describe the invention when used for neutralizing sulfite liquor as a preparatory step for the manufacture of alcohol of such liquor.

In the accompanying drawing I have

shown a vertical section of an apparatus for carrying the invention into practice.

Referring to the drawing, 1 is a reservoir provided with a supply pipe 2 for the liquor to be treated which I suppose to be sulfite liquor. The neutralizing process is suitably carried out before the liquor drawn off from the boilers has been cooled, thus for instance at a temperature of 90-95° C. As a neutralizing agent I use in well known manner powdered lime-stone, lime-mud obtained as a waste product in the sulfate pulp process or other calciferous matters said neutralizing agent being introduced into the reservoir from above. Inasmuch as it is necessary to treat large quantities of liquid, for instance 100-200 cu. m. in each charge, mechanical stirrers for keeping the lime suspended in the liquid cannot suitably be used. According to the present invention the intimate mixing of the liquor with neutralizing agent is, therefore, carried out in such manner that compressed air is blown through the liquor in the reservoir from below in a whirling motion. For that purpose a supply pipe 4 for compressed air having a valve 3 is connected to a nozzle 6 disposed at the center of the bottom 5 of the reservoir 1. The said nozzle 6 is provided with a number of helical partitions 61, for instance four, which impart a whirling motion to a fluid admitted therethrough. The bottom 5 of the reservoir 1 has suitably the shape of an inverted cone.

The compressed air introduced into the reservoir 1 through the nozzle 6 not only acts as a stirring means for intimately mixing the liquor and the neutralizing agent with each other, but also accelerates the neutralizing process by that its oxygen partly oxidizes and decomposes a number of organic compounds in the liquor, partly converts sulfurous acid contained in the liquor into sulfuric acid which reacts more easily with the lime, and calciummonosulfite into calciumsulfate whereby the precipitation thereof is accelerated. When the neutralizing process is going on, a vivid foaming takes place in the liquid caused essentially by the carbon dioxide expelled from the lime-stone by the acids of the liquor. Care must therefore be taken that the reservoir is not completely filled with liquid.

When the neutralizing process has been completed the valve 3 is closed and the solid matters of the liquid are left to sink to the bottom. Much time may be saved by draw-

ing off the clear liquid from the surface layer according as the solid matters sink downward, inasmuch as the liquid in a reservoir containing 100 to 200 cu. m. thereof 5 will require about three or four hours to be fully clear. For carrying out such drawing off of the clear liquid from the surface layer I use a siphon pipe 10 which is pivoted to a pipe 8 in the wall of the reservoir and is 10 carried by a float 11. The pipe 8 is outside the reservoir connected to a drawing off pipe 9 provided with a valve or the like 7. The siphon pipe 8 and the float 11 are arranged in such manner that the mouth of the pipe 8 15 always is held closely below the surface of the liquid. In drawing off the liquid from the reservoir 1, the valve 7 is opened as soon as a clear surface layer has been formed in the reservoir and the drawing off is then 20 regulated in such manner that the liquor is drawn off according as it is cleared. When the drawing off of the liquid is ended, the sediment forms a layer covering the bottom of the reservoir as is indicated at 17 in the 25 drawing. For removing the said sediment I flush the bottom by water in a special manner whereby I avoid the employment of mechanical stirrers. For that purpose a pipe 14 for supplying water under pressure having 30 a valve 13 or the like is connected to the nozzle 6. The pressure of the water in the pipe 14 may suitably be about 3 to 5 kg. per sq.-cm. so as to obtain a great power of the water jets flowing out through the nozzle 6. 35 These water jets describe on account of the construction of the nozzle a whirling motion and whirl up the sediment from the bottom of the reservoir. When the sediment in this manner has been completely whirled up 40 by the water admitted into the reservoir through the pipe 14 and the nozzle 6, I close the valve 13, and then the water together with the sediment contained therein is immediately drawn off from the reservoir. 45 For that purpose a drawing off pipe 16

having a valve 15 or the like is connected to the nozzle. The sediment drawn off from the reservoir in this manner contains a great percentage of calciummonosulfite and may be used in producing calciumbisulfite for 50 the sulfite pulp process. The removal of the sediment may take place after each neutralizing operation or after a number of such processes, when a larger quantity of mud has 55 accumulated in the reservoir.

The apparatus used in carrying out the above described process does not form any part of this invention but is more fully described and claimed in my patent application Serial Number 679,793, filed February 24, 1912.

Having now described my invention, what I claim as new and desire to secure by Letters Patent is:

In the preparation of sulfite liquor and other acid liquors obtained in boiling cellulose-containing materials with acid liquids for the manufacture of alcohol; the method, which comprises neutralizing a large volume of such liquor with a heavy neutralizing material, maintaining such material in suspension by a jet of compressed air having an upwardly directed rotary motion through the liquor, thereby imparting simultaneously an upward movement of the material and a 75 spiral movement toward the sides of the body of liquor thereby effecting a reaction between the oxygen of the carrying jet of air and material on the acid contents of the liquor, the material and air being simultaneously moved through the body of liquor in close contact with one another.

In testimony that I claim the foregoing as my invention, I have signed my name in presence of two subscribing witnesses.

PER GÖSTA EKSTRÖM.
